UNITED STATES PATENT OFFICE.

FRANZ GAHLEN, OF DUISBURG, GERMANY.

PRESS FOR MAKING PIPES.

1,084,881.

Specification of Letters Patent. Patented Jan. 20, 1914.

Application filed November 6, 1912. Serial No. 729,877.

To all whom it may concern:

Be it known that I, FRANZ GAHLEN, engineer, a subject of the Emperor of Germany, residing at No. 6 Manteuffelstrasse, Duisburg, Rhine, Germany, have invented certain new and useful Improvements in Presses for Making Pipes, of which the following is a specification.

Presses are already known for making pipes from an ingot, which may be either previously perforated or be perforated in the press itself by means of a perforating mandrel being forced by a plunger through an annular gap between the mandrel and the matrix. With such presses it was hitherto not always possible to produce pipes with evenly thick walls; a large portion of the pressed pipes had to be scrapped, increasing the cost of manufacture. The reason for this trouble lay in the fact, that the mandrel would assume an eccentric position in the bore of the matrix, such eccentric position being caused by the expansion of the parts of the press under the strain of the work or the influence of the heat, by warping of the mandrel and like reasons. As the mandrel will maintain the position imparted to it by the press plunger, as it is closely fitted into the same, either fixed or axially displaceable, it is obvious that the pipe pressed will have a wall of uneven thickness.

The present invention relates to a press, by which the aforementioned trouble will be avoided. The characteristic feature of this press consists in the mandrel being arranged so that it can swing in the plunger in any direction. In consequence of the mandrel's being thus able to yield in all directions, it will be able to follow the tendency of the material to always adjust the mandrel concentrically. This tendency is a result of the following circumstances: When the mandrel moves into an eccentric position, a higher specific force will be required to force the material through the narrower portion of the opening on the one side, than is required to force the material through the opposite wider side of the opening. In consequence of such difference in the specific force required the mandrel will be urged toward the axis of the matrix until the specific force is the same all around, that is until the mandrel is exactly co-axial with the matrix.

My invention further consists in rigidly guiding the mandrel during the perforating

operation and until its end is properly located in the die opening, and then releasing the mandrel so that it is free to yield, as above described. By preventing further axial or longitudinal movement of the mandrel after its end has extended into the die, a further feature of advantage is attained in that no considerable length of the mandrel is retained within the formed pipe, and there is, upon withdrawal of the mandrel, no likelihood of injury to either.

In the accompanying drawings Figure 1 illustrates a mandrel in an eccentric position with respect to the matrix, due to warping, etc., where the mandrel is rigidly secured to the plunger as in most known devices. Figs. 2 and 3 are longitudinal views, partly in section, of a press, in which the ingot is perforated by the mandrel before the pressing operation proper is commenced. Fig. 4 illustrates in longitudinal section a modified form of the invention.

In such drawings, *a* is the mandrel, *b* is the matrix, *d* is the ram, with an exchangeable press plate *d'*, *c* is the receiver and *f* is the ingot; *g* is a crosshead which can be longitudinally moved toward the press plunger *h*, and in which the mandrel *a* is secured at its rear end.

The operation of such a press is as follows: After the ingot has been introduced into the receiver, the ram *d* is advanced together with the mandrel until the perforating of the ingot is completed and the press plate *d'* almost touches the ingot. This moment is shown in Fig. 2. During such perforation the pressure of the auxiliary cylinder *i* provided in the plunger *h* acts on the crosshead *g* and thereby on the mandrel *a*. The latter is centered in a short guide *k* at the front end of the ram *d*. This guide *k* is of a little larger diameter than the front end of the mandrel determining the size of the pipe to be pressed. Before the pressing operation is commenced, the crosshead *g* is secured in known manner by means of the rods *l*, so that the mandrel will not participate in the further travel of the ram *d*. The ram *d* will now advance alone, telescope over the mandrel and the guide *k* will leave the thicker part of the mandrel, so that during the following pressing operation it can follow the aforementioned tendency of the material to move the mandrel concentrically to the matrix. In order that the mandrel

should oppose this tendency as little as possible, it is secured at its rear end in the crosshead *g* so that it can oscillate therein.

Fig. 3 shows the press at a given moment 5 during the pressing operation.

At the front end of the ram *d*, between the ram and the press disk *d*¹ a ring *m* may be provided, which is radially movable with the mandrel, and will prevent the material 10 from entering between the ram and the mandrel. In place of such ring, a ring *n* may be provided for the same purpose, outside of the press disk *d*¹.

In the form shown in Fig. 4, the mandrel 15 will participate in the whole travel of the ram *d*. In this case the crosshead *g* and the auxiliary cylinder *i* are dispensable. The mandrel is secured to the ram only, in such a manner, that it will be held coaxially to 20 the ram during the perforating operation, and can oscillate during the pressing operation. At its rear end the mandrel is centered in the ram, and at its front end in a short guide *k*, the same as shown in Figs. 25 2 and 3. During the perforating operation the mandrel will be held in its position by the resistance produced. When the perforation has been completed and the pressing commences, the mandrel will be drawn a 30 little forward by the friction caused by the material passing the mandrel and emerging from the matrix, so that it leaves the guide *k* and can now oscillate.

I claim:

35. 1. A press for producing tubes, comprising a metal receptacle, a die, a mandrel, means for forcing said mandrel through said receptacle to perforate the metal and until its end extends into the die-opening, 40 means for preventing further forward longitudinal movement of the mandrel, means for rigidly guiding said mandrel during the perforating movement and subsequently releasing it, means for forcing the metal 45 through the die and around the mandrel, and means permitting the mandrel to automatically center itself in the die.

2. A press for producing tubes, comprising a metal receptacle, a die, a self-centering 50 mandrel, means for forcing said mandrel through said receptacle to perforate the metal and until its end extends into the die-opening, means for rigidly guiding said mandrel during the perforating movement 55 and subsequently releasing it, and means for forcing the metal through the die and around the released self-centering mandrel.

3. A press for producing tubes, comprising a metal receptacle, a die, an oscillatable 60 mandrel, a crosshead to which said mandrel is connected by a universal joint, means for forcing and for guiding said mandrel through the said receptacle until its end ex-

tends into the die-opening, means for preventing further forward longitudinal movement of the mandrel, means for freeing the mandrel from said guiding-means, thereby permitting the mandrel to oscillate, and means for forcing the metal through the die and around the oscillatable mandrel. 65

4. A press for producing tubes, comprising a metal receptacle, an annular die, a mandrel, a crosshead to which said mandrel is connected by a universal joint, a hollow plunger surrounding said mandrel, said 70 plunger and mandrel having guiding-surfaces, arranged to coöperate only while the plunger and mandrel move together, means for moving said mandrel and plunger together until the end of the mandrel has 75 entered the die-opening, means for preventing further movement of the mandrel, and means for further moving said plunger to force the metal through the die. 70

5. A press for producing tubes, comprising 85 a metal receptacle, an annular die, a hollow plunger, a crosshead having a mandrel connected thereto by a universal joint, said mandrel extending through the opening in the plunger, the wall of said opening being contracted at its lower end to form a guiding-surface for an enlarged portion of said plunger, means for moving said plunger and mandrel together until the end of the mandrel has entered the die-opening, means 90 for preventing further movement of the mandrel, and means for further moving said plunger to force the metal through the die and around the mandrel. 95

6. A press for producing tubes, comprising 100 a metal receptacle having an annular die, a self-centering mandrel, means for moving said mandrel through the receptacle to perforate the metal and enter the die, a plunger surrounding said mandrel 105 adapted to press the metal through said die, said mandrel projecting loosely through the end of the plunger, and a slidably metal-retaining ring on the face of said plunger and around said mandrel. 110

7. A press for producing tubes, comprising 115 a metal-receptacle having an annular die, an oscillatable mandrel, means for moving said mandrel through said receptacle to perforate the metal, a plunger surrounding said mandrel adapted to press the metal through said die when the forward end of the mandrel has reached said die, means for rigidly maintaining said mandrel centrally of said receptacle during the perforating step, means for releasing said mandrel to permit it to oscillate when said plunger is operated, and a metal-retaining ring fitting around said mandrel and slidably engaging the face of said plunger. 120

8. A press for producing tubes, comprising 125

ing a receptacle for holding metal to be perforated, a die, a plunger, a mandrel in said plunger, said plunger constructed and arranged to rigidly center said mandrel during the perforating step and subsequently to release said mandrel from its rigid position, said mandrel projecting loosely through the end of said plunger and free

to oscillate therein during the pressing after its release from said rigid position.

In testimony whereof I affix my signature in presence of two witnesses.
